LUGGAGE HANDLE

Joseph Finkelstein, Glenside, Pa., assignor to Philadelphia Brief Case Company, Philadelphia, Pa., a partnership

Filed Mar. 23, 1959, Ser. No. 55,106

Term of patent 14 years

(Cl. D87—2)

Fig. 3.

Fig. 1.

Fig. 4.

Fig. 2.

I claim:

The ornamental design for a luggage handle, substantially as shown.
